UNITED STATES PATENT OFFICE.

ROSWELL T. SMITH, OF NASHUA, NEW HAMPSHIRE.

EMBROIDERING-MACHINE.

SPECIFICATION forming part of Letters Patent No. 377,411, dated February 7, 1888.

Application filed March 26, 1887. Serial No. 232,552. (No model.)

To all whom it may concern:

Be it known that I, ROSWELL T. SMITH, a citizen of the United States, residing at Nashua, in the county of Hillsborough and State of New Hampshire, have invented certain new and useful Improvements in Embroidering-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to that type of embroidery-machines in which the needles are passed alternately in opposite directions through the web upon which the design is worked, the entire range or series of needles being transferred from a traveling carriage upon one side of the web to a similar carriage upon the opposite side. These carriages move upon a railway, within which and transversely thereto the web is stretched upon a tambour-frame, which is moved in different directions to give the proper formation to the stitch. These carriages are drawn toward the tambour-frame by weighted cords connected to each carriage, but their retrograde movement is derived from a pair of belts carried by sprockets upon a power-shaft at one end of the railway. These belts move freely through projecting brackets on the needle-carriages, but each one is provided with a boss or block rigidly mounted on the belt and interposed between the two carriages. As the belts travel in either direction, these blocks make contact with the brackets on one or other of the carriages, and move said carriage from the web to the extent of the working-threads, thereby drawing the stitch up with the requisite tension. At this point the retrograde movement of the carriage must cease and it must return to the web, which in the meantime has been moved to such position that the needles entering it will form the ensuing stitch. The penetrating ends of the needles are then grasped by the needle-jaws of the other carriage, and the operation is repeated and continued until the design is completed. This is briefly the construction and operation of machines of the Swiss type, commonly called the "Heileman ma-

chine," and substantially the same general mode of operation has been adopted in many other machines of later date.

It is evident that as the operation of the machine continues the threads carried by the needles are constantly decreasing in length as they are consumed in the incorporation of the design in the web stretched upon the tambour-frame. This decrease in the common type of machine is not a constant quantity or factor, since but few of the stitches formed are of equal length, and it is evident, therefore, that the retrograde movements of the needle-carriages will constantly decrease in extent, and that, in order to reverse such movements at the proper instant, and at the same time completely form the stitch and preserve a uniform tension of the working-threads throughout the process, the successive points of reversal must be determined by the thread-tension and must be automatic. Various ways have been proposed for effecting this result—as, for example, in my applications for Letters Patent filed June 10, 1885, and July 9, 1886, pending concurrently herewith and numbered in serial 168,237 and 207,609, in which I effect the reversal by mechanism brought in action by closing an electric circuit, this being effected by the vibration of a tension-bar resting upon the working-threads in the one case, and by the vibration of a lever caused by the swaying of the web in the other case. While the electric current thus applied produces excellent results, the substitution of some less expensive power is desirable, not only by reason of its economy alone, but because of the necessity of keeping the electrical contacts perfectly free from dust or other foreign matter which might possibly cause them to fail in action.

It is the purpose of my present invention, therefore, to provide simple and comparatively inexpensive mechanism for effecting the automatic reversals of the "railway" in embroidery-machines, which shall operate instantly and with the same accuracy and uniformity of thread-tension secured by the electric apparatus.

To this end my invention consists in the several novel features of construction and new combinations of parts hereinafter fully set forth, and definitely pointed out in the claims following this specification.

Referring to the drawings which accompany this application, Figure 1 is a longitudinal vertical section of part of an embroidering-machine illustrating my invention, those familiar portions of the mechanism not required being omitted. Fig. 2 is a plan view of a part of Fig. 1. Fig. 3 is a detail section of the head of the needle-carriage, the arm, needle-jaws, and needles being shown in dotted lines. Fig. 4 is a detail plan view of the bracket and valve shown in section in Fig. 3. Fig. 5 is a detail perspective of the parts shown in Figs. 3 and 4, showing the manner of operation. Fig. 6 is a detail of a portion of the plan view shown in Fig. 2. Fig. 7 is a view of a modified construction.

In the said drawings, the reference-numeral 1 designates the frame of the embroidering-machine, which is of ordinary or any desired construction, and adapted to support the railway 2. Midway of the latter, or thereabout, is erected a frame, 3, within which the tambour-frame receives support and adjustment by any suitable apparatus, but preferably by the automatic stitch adjustment covered by my pending application filed March 25, 1887, and numbered in serial 232,375.

Upon the railway 2 are mounted needle-carriages 4, of any type, the form shown being substantially that adopted in my application filed July 9, 1886, Serial No. 207,609. Each of these carriages is drawn toward the web or tambour-frame by cords 5, running over pulleys on the frame and weighted, while the retrograde movement is produced by belts 6, driven by pulleys 7 on a shaft, 8, at one end of the railway, all of said parts being essentially similar to the corresponding features shown in my application last above mentioned.

Upon each needle-carriage 4 is a pivotal axis, 9, which carries the movable jaws of the needles. Upon said axis are pivotally mounted arms 10, curving over and in front of the needle-range, and supporting at their free extremities a tension-bar, 11. In Fig. 5 I have shown the arms 10 as carried by a collar, 12, confined between two rigid collars, 13, which prevent lateral movement, but permit the arms to swing freely up and down. While this is a convenient form of a construction, any other giving a similar result may be used instead, the length and form of the arms 10 being such as to permit the tension-bars 11 to rest upon the threads 14 in about the position shown in Fig. 3.

Projecting from the carriage-arm 4 is a bracket, 16, (shown more clearly in Figs. 3 and 4,) and depending from said bracket is a nipple, 17, adapted to receive the end of a flexible tube, 18. Communication is made through the bracket by an opening, 19, entering the nipple, which is closed by a valve, 20, swinging upon a pivoted axis, 21, and normally shut by a spring, 22, the swing of the valve produced by the spring being limited by a stop, 23. In the end of the valve-plate is formed a

notch, 24, and the end of the plate upon that side of the notch farthest from the stop 23 is beveled off, as shown at 25, Fig. 4. An elastic arm, 26, depending from the collar 12 of one of the tension-arms 10, and rigidly mounted on said collar, has a loose engagement with the notch 24, the construction being such that as the tension-bar 11 rises or vibrates forward under the tension of the threads 14 the valve will swing forward far enough to not only uncover the opening 19, but to draw the end of the arm 26 out of the notch 24, thereby permitting the valve to snap back into place under the tension of the spring 22, this being the purpose of the bevel 25.

Upon the shaft 8, which drives the pulley 7, operating the railway-belts, are mounted two pulleys, 27 and 28, of equal diameter. These pulleys are loose upon the shaft 8, and are belted to the power-shaft in such manner that they revolve in opposite directions, the connection shown being by a straight belt, 29, and a cross-belt, 30. Upon each pulley is a clutch-box, 31, and keyed to the shaft 8 are clutches 32, adapted to engage with the boxes 31 and lock either pulley 27 or 28 to the shaft. These clutches are thrown into and out of gear by clutch-levers 33, having forked extremities 34, running in a channel, 35, in each clutch. The clutch-levers are each fulcrumed upon a bracket, 36, mounted on the frame 1, and their lower ends have positive engagement with a reversing-bar, 37, whereby as one clutch is thrown into the other is simultaneously thrown out of engagement, thus releasing one of the pulleys 27 28 at the same instant that the other is locked to the shaft. The reversing-bar 37 may be pivotally connected to the ends of the clutch-levers 33, and thus be supported by them.

The clutch-levers 33 being thrown by the reversing-bar 37, it now becomes essential to impart the necessary longitudinal movement to this bar at proper times, and this I accomplish in the following manner: Upon any suitable supports, 38, are journaled two independent shafts, 39, upon each of which is keyed a pulley, one of said pulleys being designated by the numeral "40" and the other by the numeral "41." Both receive a like rotation by pulleys 42, belted to the power-shaft, and both revolve continuously. Underlying these pulleys are casings 43, which partly surround the periphery of each pulley, a suitable space being left between to admit an elastic belt, 44, and permit it to leave the surface of the pulley. This belt nearly surrounds the bearing-surface on each pulley; but one end, 44^a, is unattached and is brought up in front of the revolving pulley, and at or near this extremity a cord or wire, 45, is attached, running over a friction-pulley, 46, and connected to a spring, 47. The belt from this point is led around the pulley 27 or 28 and carried over the free end 44^a of said belt, a spring, 48, being connected thereto and to a bracket-base, 50^a.

At or near its extremity the belt 44 is con-

5 nected with one arm, 49, of a bell-crank lever fulcrumed on the head of a T-bracket, 50, supported by the machine-frame. The connected end of said arm has a slot, 51, running on a pin, 51^a, on the belt to permit free swing to the arm. The other arm, 50^a, of said bell-crank engages a stud, 52, on the reversing-bar 37, which, by the swing of said arm, is thrown longitudinally to operate the clutch-levers 33.

10 A similar connection is made from the corresponding arm, 49^a, of the other bell-crank, which may conveniently be curved to pass the fulcrum of the other and similar lever, and the angular arm of said bell-crank has a like connection with a stud, 52^a, on the reversing-bar.

15 Belt-guides 53 may be placed on the casings 43, and in all essential respects the construction does not materially vary from the clutch-pulleys shown and claimed in my application 20 of July 9, 1886, hereinbefore named, and in the application filed upon the 17th day of September, 1885, Serial No. 177,404, and renewed April 25, 1887, Serial No. 236,082.

It is the peculiar function of this apparatus 25 that by creating even a moderate frictional contact between the pulley and the free end 44^a of the belt 44 a strong draft will instantly be produced at the other end, which will be continued as long as the free end is pressed 30 upon the revolving pulley. The described construction and arrangement are the same in the case of the other pulley, and the operation thereof is, under like conditions, the same as that described.

35 Mounted upon a pivotal bearing, 54, is an arm, 55, in the end of which is journaled an idle-roll or friction-roll, 56, the arrangement being such that said roll stands only a little below the free extremity 44^a of the belt 44. 40 This arm has belt-guides 57, and it is normally impelled away from the end 44^a of the belt by a spring, 58. Bearing against the outer face of the arm 55 is a slide-bar or piston-rod, 59, carried in a bearing, 60. The 45 other end of said bar lies in a cylinder, 61, of any suitable diameter, and on the end of said bar is mounted a piston-head, 61^a, which fits and moves in the chamber 62 of an air-engine. Communicating with the chamber is an exit- 50 pipe, 63, which connects with a bellows, air-pump, or blower, or any means for exhausting the chamber 62, the mechanism shown being an exhausting-bellows of any construction, as shown at 64. This bellows is worked by a suitable crank and pitman on the power-shaft, or 55 it may be on a counter-shaft.

While the exhaust-pipe 63 communicates with the chamber 62 on one side of the piston-head 61, an equilibrium is established by openings 64 in the piston-head of a size adapted to the exhaust of the pump or bellows 65. Entering the head of the cylinder 61, on the other side of the piston-head from the exit or exhaust-opening leading to the pipe 63, is an 65 opening, 66, which communicates with the pipe 18.

It being remembered that the mechanism

last described is duplicated in connection with the other clutch-operating pulley 41 so far as the vibrating arm 55, piston 59, and air-engine 61 are concerned, the operation of the mechanism is as follows: As the needle-carriage 4 recedes from the web to the length of the threads, the vibration of the tension-bar 11 operates the valve 20 and admits air to the tube 18 through the opening 19. This at once destroys the equilibrium of atmospheric pressure upon both faces of the piston-head 61, and the preponderating weight instantly drives the piston-head toward the exhaust-opening 63^a, thereby actuating the piston 59 and throwing the idle-roll 56 against the end of the belt 44, producing an instantaneous and powerful draft on the said belt, which instantly operates one of the bell-cranks 49 or 49^a and throws the reversing-bar 37, whereby the one pulley 27 is locked to the shaft and the other 28 released therefrom, or vice versa. As the tension-bar 11 swings the valve 20, the arm 26 passes out of the notch 24 in the end of the 90 valve, and the latter instantly draws back to place by the spring 22. The tension-bar 11 shortly afterward returns, and may at once do so, the end of said arm riding over the bevel 25 until it reaches the notch 24, when it snaps 95 into engagement with the latter by the elasticity of the arm. The action of the piston-rod 59 effects an instantaneous longitudinal movement of the reversing-bar 37, by which the clutch-levers 33 are both operated, the one 100 to engage and the other to disengage the respective clutches 32. After the reversing-bar is once thrown in either direction it tends to remain in such position until positively actuated in the opposite direction, a sufficient 105 frictional bearing being provided at the fulcrum 36 to hold each lever in either position. The action of the valve 20 on the needle-carriage being practically instantaneous, the idle-roll 56 on the vibrating roll-carrier 55 acts on the belt 44 for a moment only; but this time is amply sufficient to operate the corresponding bell-crank 49 or 49^a and effect the reversal. As the valve 20 closes and restores the equilibrium of atmospheric pressure upon both 110 sides of the piston-head 61^a, the piston 59 is restored to its position by the spring 58. The instant that the end 44 of the belt is released from positive contact with the surface of the pulley the action of the spring 47 throws it 115 off the revolving pulley and checks the draft on said belt sharply and suddenly by effecting its complete disengagement from the pulley. The spring 48 then swings the bell-crank 120 which has been actuated back to place.

125 Should the strain upon the belt 44 continue after reaching the maximum, the pulley 41, carrying said belt, will slip between friction-disks 41^a, which are keyed on the shaft 39 and clasp the flat faces of the pulley, as fully set forth in my prior applications referred to. This slip continues as long as the end 44^a of the belt is in positive contact with the pulley surface.

As the carriage approaches the web, it is necessary to raise the tension-bar 11 and throw it backward to allow the needles to pass through the fabric, and this is accomplished by a lift, 67, rigidly fastened on the collar 12, one at each end of the carriage. These lifts engage with pins 68, carried by bars 69 on the frame B, and these pins enter the ways or channels 70 in the lifts and turn the tension-bar entirely out of the way, restoring it to its position again as the carriage begins to recede from the web.

In order to apply the foregoing apparatus, two distinct air-engines or exhaust-cylinders 61 are necessary, as already stated, each having a piston-rod, 59, operating on a separate roll-carrier, 55. I have shown but one of these cylinders in Fig. 2, inasmuch as the other is an exact duplication in all respects of that shown.

The two clutching-pulleys 40 and 41 are essentially the same as the similar mechanism covered by my application filed July 9, 1886, No. 207,609, save that in place of throwing the roll-carrying lever 55 toward the pulley by the action of an energized electro-magnet I employ the force produced by the exhaust, as described. As regards the mechanical results, the substitution of the pneumatic for the electric force is preferable both on account of economy and certainty of action, and it is in all important particulars equal to the electric devices.

The particular construction of the air-engine 61 and of the exhausting mechanism may be very considerably varied, since said parts may be either new or of known construction. I may exhaust the chamber 62 by an ordinary blower or a cylinder-pump. I may also employ any form of valve mechanism, and may greatly modify the reversing mechanism shown. In short, my invention consists in the substitution of pneumatic in place of the electric energy for effecting the reversals of the railway, and not in any specific mechanism by which such substitution is effected.

It is apparent that the clutch-pulleys 41 might be dispensed with, if desired, and the piston-rods of the air-engines connected to the reversing-bar 37 direct. The interposition of the clutch-pulleys between the air-engines and the reversing-levers is for the purpose of gaining power and securing the necessary action of the reversing devices with a very limited movement of the piston-head 61^a. With the clutch-pulleys a movement of barely the eighth of an inch will secure an instant response from the pulley, and the air-openings 64, as well as the conduits 18 and 63, may be of comparatively small size. This enables me to employ an exhaust of low power and to actuate the valves on the needle-carriages by a light tension of thread.

In Fig. 7 I have shown a modified arrangement by which the clutch-pulleys and clutching mechanism may be dispensed with. In this case I employ a simple belt-shifter, 71,

actuated by bell-cranks 72 in such manner as to throw the shifter in opposite directions. The belt 73 is operated by runs over a loose pulley, 74, on each side of which is a wide pulley, 75, belted one by a straight and the other by a cross belt to the pulleys 76 on the railway-shaft. By giving the belt 73 a rapid motion and making the pulleys 76 of sufficient diameter to compensate for this increased speed this construction will be practicable. The levers 72 will be operated by the piston-rods 59 direct, though the clutch-pulleys 41 may be interposed, if desired.

What I claim is—

1. In an embroidering-machine, the combination, with the needle-carriages and the mechanism whereby they are moved toward and from the web, of pneumatic devices controlled by the tension of the working-threads by which the needle-carriages are reversed automatically, substantially as specified.

2. In an embroidering-machine, the combination, with the needle-carriages and mechanism by which they are moved to and from the web, of reversing mechanism operated by pneumatic mechanism controlled by the thread-tension, said mechanism consisting, essentially, of an air-cylinder, a perforated piston-head 95 moving therein, an air-entrance on one side of said piston-head and an air-exit on the other, an air-pump connecting with the cylinder, and a valve controlled by the thread-tension, whereby the equilibrium of atmospheric pressure on both sides of the piston-head is disturbed, substantially as specified.

3. In an embroidering-machine, the combination, with the needle-carriages and the mechanism by which they are caused to recede from the web, of devices by which said mechanism is reversed, a pneumatic exhaust, and a valve mechanism on the needle-carriage operated by devices connected with the embroidering-threads, whereby the reversing devices are 110 actuated, substantially as specified.

4. In an embroidering-machine, the combination, with the needle-carriages and the mechanism by which they are alternately moved from the web, of levers which actuate the reversing devices, a pneumatic engine consisting of a cylinder and a perforated piston moving therein, a flexible tube connection between the engine and the needle-carriage, and a valve actuated by the tension of the embroidering-threads to open said valve and admit air to the air-engine on one side of the piston-head, substantially as specified.

5. In an embroidering-machine, the combination, with needle-carriages which recede 125 from the web alternately, and with traveling belts effecting such movements, of oppositely-revolving pulleys, by which revolution in opposite directions is given the shaft driving said belts, clutching mechanism whereby one 130 of said pulleys is locked to as the other is unlocked from the shaft, cylinders having perforated piston-heads and piston-rods connected with the clutching mechanism, an exhaust for

each cylinder on one side of the piston-head, an air-conduit entering the cylinder on the other side, and a valve on the needle-carriage operated by the working-threads, whereby the 5 equilibrium of atmospheric pressure is disturbed and the reversing mechanism actuated, substantially as specified.

6. In an embroidering-machine, the combination, with railway-belts and pulleys operating the same in opposite directions alternately, of devices whereby one of said pulleys is caused to act as the other ceases, an air-cylinder having connection by its piston with said devices, means for exhausting the cylinder 15 upon one side of the perforated piston-head, an air-conduit entering the cylinder on the other side, and means for opening and closing said conduit controlled by the embroidering-threads, substantially as specified.

20 7. In an embroidering-machine, the combination, with the needle-carriages and mechanism for moving said carriages from the web, of oppositely-revolving pulleys, by which the retrograde movement is arrested, clutches 25 having simultaneous action, whereby one pulley is locked to as the other is unlocked from their shaft, air-cylinders having a continuous exhaust upon one side of their perforated pistons and an interrupted air-supply on the 30 other side, and means for controlling the latter arranged upon the carriages and actuated by the working-threads, substantially as specified.

35 8. In an embroidering-machine, the combination, with a railway-shaft and belts driven thereby, of oppositely-revolving pulleys, clutching mechanism on the shaft of said pulleys, a clutch-throwing lever operating the same, air-cylinders having perforated piston-heads, means for exhausting from one side and giving an interrupted air-supply on the other side of said piston-heads, valves on the needle-carriages which control said supply, tension devices operating the valves, and intermittently-acting pulleys interposed between the 45 air-cylinders and the clutch-levers, substantially as specified.

40 9. In an embroidering-machine, the combination, with reversing mechanism by which the 50 needle-carriages are caused to recede from the web, of air-cylinders having perforated piston-heads, an air-exhaust upon one side of said piston-heads, air-conduits entering the cylinders on the other side, valves mounted on the carriages opening and closing the said conduits, tension-bars resting on the working-threads, and devices actuated by the rise of said bars to 55 open the valves, substantially as specified.

55 10. In an embroidering-machine, the combi-

nation, with alternately-operating air-engines 60 which actuate the railway-reversing devices, of air-conduits connected to the needle-carriages, spring-actuated valves closing the said conduits, and arms swung by the rise and fall of tension-bars resting on the threads to open the 65 valves, substantially as specified.

11. In an embroidering-machine, the combination, with mechanism reversing the railway, of air-cylinders having alternate action, perforated piston-heads moving in each cylinder, an 70 exhaust-passage on one side and a flexible air-pipe mounted on each carriage and entering on the other side in each cylinder, a valve on each carriage closing one of said pipes, tension-bars rising and falling with the threads, and 75 flexible arms vibrated by said bars to open the valve, substantially as specified.

12. In an embroidering-machine, the combination, with the needle-carriages and the tension devices carried thereby, of the pivoted 80 spring-actuated valve-plates, each having a notched and beveled end, an elastic arm carried by the tension device, and means for raising the latter as the carriages approach the web, substantially as specified. 85

13. In an embroidering-machine, the combination, with oppositely-revolving pulleys giving reverse revolution to the railway-shaft, of clutches keyed to said shaft and having simultaneous opposite action, one locking and the 90 other unlocking one of said pulleys, a reversing-lever actuating said pulleys, intermittently-acting pulleys reciprocating said lever, a pneumatic engine effecting an operative engagement between each pulley and its belt, and 95 means for controlling the action of said engines operated by the tension devices on the needle-carriages, substantially as specified.

14. In an embroidering-machine, the combination, with the pneumatic cylinder, of the 100 exhaust-pipe 63 and inlet 18 at opposite ends, the perforated piston-head, the piston-rod, the reversing devices operated thereby, the valve on the needle-carriage, and the tension-bar, substantially as specified. 105

15. In an embroidering-machine, the combination, with the air-cylinder 61, having an air-exhaust, 63, at one end and an air-inlet, 18, at the other, of the perforated piston-head 61^a, piston 69, roll-carrier 55, belt 44, pulley 41, 110 and spring-actuated valve 20, substantially as specified.

In testimony whereof I affix my signature in presence of two witnesses.
